CLAIM

The ornamental design for a fishing rod, as shown and described.

DESCRIPTION

FIG. 1 is a side elevational view of a fishing rod, showing my new design, the opposite side being a mirror image thereof;

FIG. 2 is a top side and rear perspective view with a portion of the rod omitted for the convenience of illustration; and,

FIG. 3 is a bottom, side and rear perspective view thereof.

FIG.1

FIG.2

FIG.3
